SKI FASTENING

Paul Schwarze, Saint Gallen, Switzerland

Application February 6, 1941, Serial No. 377,691
In Germany August 9, 1939

4 Claims. (Cl. 280—11.35)

1

The attachment of the boot to the ski is generally effected by a strap passed and tightened around the heel whereby the front part of the boot is forced between jaws. For the good control of the ski in downhill running it is important that the back part of the boot is firmly pressed to the ski. Previous constructions, however, have the disadvantage that when the back part is swung upwards the tension is continuously increased and with it the force opposed to a further upward swing. As the tension is already very strong in the original position, swinging upwards over a comparatively small angle is practically impossible. If the skier using such a binding should have a fall he runs the risk of considerable injuries, as he cannot liberate himself from the binding.

The present invention is an improvement over and above the prior propositions and consists in means which draw the rear part of the boot towards the ski in such a way that the force acting against the upward movement of the boot heel does not continuously increase. A preferred embodiment consists in a spring which is mounted or formed in such a way that its parts come into springy action successively when the boot heel is raised.

In the accompanying drawing several embodiments of the invention are illustrated by way of example. Fig. 1 is a side elevation of the centre part of the ski with the boot and a spring acting on the latter. Figs. 2 and 3 are side elevations of other embodiments. Figs. 4, 5 and 6 are details of the fittings of Fig. 3. In Fig. 1 the ski is indicated by 1, its forward part being on the left of the drawing. 2 is the boot with its front part secured between the jaws 9. The heel of the boot is coupled to the spring 4 by the fitting 3. The plate-shaped spring lies on the ski and is capable of sliding along it. It is held by the bridge 5 the upper part of which is conveniently formed as a roller. The back end 6 of the spring may be bent upwards in order to find a check at the bridge 5 when sliding forwards. 7 is a stop on the ski to prevent the spring from sliding backward more than is necessary.

The spring offers resistance to the upward movement of the boot heel and this resistance can be adjusted by altering the distance between the bridge 5 and the boot. During the upward movement of the heel the fitting 3 which is fastened to the boot and coupled to the spring takes the latter with it so that the springy part in front of the bridge is extended. While, therefore, the upward movement causes an increase-

2

ing spring tension, this increase is counterbalanced by the fact that the part of the spring causing the tension is lengthened. The equipment can be so arranged that when the rear end 6 of the spring strikes the bridge 5 or when the heel of the boot has reached a certain height the coupling between the fitting 3 and the spring 4 is automatically disconnected so that the skier is free if he falls.

10 In Fig. 2 the spring consists of several plates which can be so arranged that when sliding forwards the plates are freed one after the other from the bridge 5 so that finally only one plate is held by it. The spring may remain flat at the 15 rear end so that when the skier falls it can slip out of the bridge and be taken along with the boot. The bridge 5 is adjustable in such a way that the effective spring length or its tension can be altered. This is done in the embodiment shown 20 in Fig. 2 by supplying the bridge with a set-screw by which the distance of the spring from the ski can be changed.

Fig. 3 shows another advantageous embodiment consisting in a special shaping of the spring. It 25 is formed of three parts of which the two parts 11 and 12 behind the heel are directed upwards and downwards whereas the third part 13 is arranged at an angle to the first two parts. The three parts are riveted together or so connected 30 that they can easily be disconnected for better transport and re-assembled. An upward movement of the heel is first resisted by the great strength of the part 13 which can be reinforced by additional spring plates. The more, however, 35 the heel is swung upwards the more do the parts 11 and 12 get into action by their displacement, so that the increasing tension is counterbalanced by the enlargement of the effective spring parts. According to Fig. 3 the adjustment of the spring 40 is effected by a cam lever 8 with which for downhill running the spring can be so pressed to the ski that a considerable tension is already effected when the heel of the boot is still on the ski. In the embodiment shown in Fig. 3 the fitting 3 45 snaps automatically into a recess of the spring part 11 when the heel is depressed. As shown in Fig. 4 the fitting 3 is a small plate attached to the boot and has a nose 14 projecting towards the spring. The lower part of the spring 11 in this figure is in longitudinal section, also in Fig. 50 5 which shows the same arrangement as Fig. 4, but with the boot heel in a raised position. From the latter and the shape of the recess 15, which is shown in the front elevation of the lower part 55 of the spring 11 in Fig. 6 it will be seen in what

way the end of the spring 11 can slip off the nose 14 when the boot heel has reached a certain height.

The front part of the boot can be introduced between the customary jaws which are fitted with a leather strap. But it is of considerable advantage to employ a coupling according to my U. S. Patent 2,192,870, as in this case the distance between the jaws and the spring can be properly fixed in accordance with the size of the boot and the whole binding can thus be securely adjusted. By the combination of the present invention with such a coupling of the front part of the boot to the jaws a hitherto unattained control of the ski is ensured and at the same time the safe release of both the rear and front part of the boot at the otherwise dangerous forward fall. In all embodiments it is of course possible that in the beginning of or during the upward movement of the boot heel the counteracting force is increased for a small distance. This does not influence the scope of the present invention which is not confined to the species shown and described but comprises all ski fastenings which embody the idea of a spring which does not allow the resistance to the upward movement of the heel to continuously increase.

I claim:

1. Ski fastening comprising jaws on the ski for the front part of the boot; a spring acting on the rear part of the boot in such a way that when the heel of the boot is moved upwards its parts come into springy action one after the other; whereby a continuous increase of its resisting force is prevented; and a fitting on said boot heel adapted to become automatically coupled to said spring when said heel is depressed.

2. Ski fastening comprising jaws on the ski for the front part of the boot; a spring acting on the rear part of the boot in such a way that when the heel of the boot is moved upwards its parts come into springy action successively; means to adjust said spring; and means attached to the rear part of the boot for coupling it to said spring, said means being adapted in such a way that said boot is automatically released from

said spring when the heel is raised over a predetermined angle.

3. Ski fastening comprising means on the ski adapted to engage the front part of the boot; a spring on the ski acting on the rear part of the boot in the sense of drawing it towards the ski, said spring being formed of two parts which extend up- and downwards and a third part which is arranged at an angle to the first two parts said up- and downwards extending parts being adapted in such a way that during the first period of the upward movement of the boot heel they act as unbending members and subsequently come into springy action by their displacement, thereby counteracting the otherwise continuous increase of the tension.

4. Ski fastening comprising means on the ski for engaging the front part of the boot; a spring adapted to be attached to the ski and to the rear part of the boot, said spring forcing the boot to the ski in such a way that when the heel of the boot is swung upwards the counteracting force of said spring does not continuously increase; a bridge on the ski for holding said spring; and a cam-lever at said bridge for adjusting the tension of said spring.
